PADDING STRIP FOR FURNITURE AND
OTHER ARTICLESJames Duvall, Camas, Wash., assignor to Crown
Willamette Paper Company, San Francisco,
Calif., a corporation of Delaware

Application June 1, 1934, Serial No. 728,519

4 Claims. (Cl. 154—54)

The object of my invention is to provide a padding strip, especially adapted for use for furniture, inexpensive, easily applied, and adapted to hold itself temporarily in place, until tied or otherwise secured, on the edges of a flat horizontal surface, as, for example, the edges of a table or desk; and further adapted to prevent uneven pressure being applied to certain portions of the surface covered by the pad due to unevenness of the pad. Such uneven pressure is frequently caused by other types of padding used on furniture, and tends to cause mars on the furniture surface.

I attain my object in a padding strip comprising a cushion layer composed of relatively soft pliable, preferably crinkled liner-sheets of paper, and a cover sheet of paper of stronger texture, the lateral edges of said cover sheet being folded over and secured to the lateral edges of the top of said liner sheets; and by making my padding strip in such manner that its lateral portions tend to fold or come together on a longitudinal medial line. This latter characteristic is one of the essential features of my padding strip, and I obtain this by forming in my padding strip a permanent, longitudinal medial crease. These details, and other incidental features, of the construction of my padding strip I have hereinafter fully described with reference to the accompanying drawings.

In the drawings:

Figs. 1 to 4 inclusive illustrate the construction of, and the different steps and stages for making my padding strip;

Fig. 5 illustrates the method of using my liner strip for protecting an edge of a flat surface such as a table or desk, and further illustrates how my padding strip tends to hold itself in place preliminarily to being tied or otherwise;

Fig. 6 illustrates a method of folding and rolling up my padding strip for shipment or storage, so as to retain in the strip the longitudinal medial crease, and the tendency of the lateral portions to fold or come together;

Fig. 7 shows a diagrammatic side elevation of a machine for making my padding strip;

Fig. 8 is a top view of said machine;

Fig. 9 is a cross-section on line 9—9 of Fig. 8; and

Fig. 10 illustrates the difficulty encountered in the use of a similar padding strip without the longitudinal medial crease.

As shown by my Fig. 1, my liner strip comprises a cushion layer composed of sheets of relatively soft, preferably crinkled liner sheets *a*, *b*, *c* and

d, for example, placed one over the other, and a cover sheet *e*. The lateral edges *e'*, *e2* of the cover sheet are folded over and secured to the lateral edges of the upper liner sheet *a*, as illustrated in Fig. 2. The pad is then provided with a longitudinal medial crease *f* and this crease must be permanently set in the strip so that the lateral portions of both sides of the said longitudinal medial crease *f* tend to come together as illustrated by Fig. 4. Said permanent set of the crease *f* may be produced in various ways, of which I will describe those found more practical by me.

For example, the strip may be stitched as indicated by stitches *g* along the line of said longitudinal medial crease in Fig. 4, or the innermost liner-sheet *d*, that is to say, the one adjacent to the cover sheet *e* may be pasted to the latter along said longitudinal medial crease line *f*. I find it also an advantage for the purpose of permanently setting said crease and causing the lateral portions of the padding strip to tend to come together as mentioned to make the liner-sheets *a*, *b*, *c* and *d*, progressively wider in their order of approach to said cover sheet *e*.

For the purpose of making my liner strip I employ a machine as illustrated by Figs. 7, 8 and 9. It comprises a table section *h* over which are fed sheets of soft, pliable, preferably crinkled paper from rolls *i*, *j*, *k*, *l*. These sheets are drawn under a shoe *m* into a folder *n*. Underneath the sheets passing from said rolls into the folder *n* extends a sheet of paper of stronger texture which is to constitute the cover of one face of the cushion layer of my padding strip, such cover sheet being drawn from a roll *p* over guide rolls *q*, *r* and while passing over the guide roll *r* the lateral edges of the cover sheet *e* each have a strip of paste applied thereto from a paste pan *s* in which runs a paste roll *t*, the latter adapted to apply paste only to the lateral edges of the cover sheet *e*, as mentioned. However, if it is desired to paste the cover sheet to the adjacent liner-sheet along the longitudinal medial crease line, the paste roll would, of course, be correspondingly constructed to apply the required additional strip of paste at the center of the cover sheet. The lateral walls *n'*, *n2* of the folder *n* are adapted to fold the lateral edges of the cover sheet *e* over and paste the same to the edges of the uppermost sheet *a*. For such purpose the walls *n'*, *n2* at the receiving end of the folder *n* are perpendicular and then are curved inward so that at the outgoing end of the folder said walls are arranged as shown by the cross-section in Fig. 9. The padding strip, upon leaving the folder *n*, is

drawn between two creasing rolls v , v' , the lower v' of which has a shallow, central, circumferential groove as at v_2 , Fig. 8, and the upper roll v of which is provided with a V-shaped circumference as illustrated by Fig. 8. From the creasing rolls v , v' the pad, indicated by w , passes between two draw rolls x , x' , the upper roll x of which has a groove as at x_2 so as not to iron out the crease f produced by the creasing rolls v , v' , along the longitudinal middle line of the strip.

As the padding strip is completed it is folded on the longitudinal medial crease and kept in this condition until used. For convenience in handling, shipping, or storing it may be rolled up as indicated in Fig. 6. In such case it is desirable to roll the strip on a core with a diameter of at least 8 inches. The rolling up of the strip in this way not only retains the longitudinal medial crease and the tendency of the lateral portions on both sides of the crease to come together, but makes the strip very convenient for handling since it can be unrolled as used and cut off into any lengths desired.

The utility and convenience of my padding strip are further apparent with reference to Fig. 10, which illustrates a similar padding strip made without the longitudinal crease and without any tendency to fold together. In this figure the strip of padding y is shown placed on the edge of the table z but if too much of the strip extends beyond the edge of the table the strip becomes over balanced and falls off, as shown by the dotted line. It will be clear in referring to Fig. 5 that this annoyance is completely eliminated by the special feature which the longitudinal crease constitutes. It is also evident that my creased padding strip is particularly suitable for corners and easily applied to such places.

While my padding strip is especially designed for padding furniture for shipment, etc., it is also useful in the shipment of plumbing fixtures and other articles, since it forms a very efficient and protective padding and requires a relatively smaller crate than is required when most of the other kinds of padding are used for such articles. While it is not necessary that the liner sheets of my padding strip be crinkled or creped paper, it is preferable that they should be since the creping causes air to be entrapped and renders the individual sheets of paper, and consequently the entire padding strip, more cushiony.

Another advantage of my padding strip is that it has practically no fire hazard as compared with paddings using excelsior or shredded newspaper.

I claim:

1. A padding strip comprising a cushion layer composed of relatively soft pliable liner-sheets of paper and a cover sheet of paper of stronger texture covering one face of said cushion layer, the lateral edges of said cover sheet being folded over and secured to the lateral edges of the top of said liner-sheets, the padding strip provided with a longitudinal medial crease adapted to fold the lateral portions of the strip against each other, whereby the padding strip when opened out on its said crease and placed over an angular surface will tend to be temporarily held in place by the reflex action of its lateral portions. 10

2. A padding strip comprising a cushion layer composed of relatively soft pliable, crinkled liner-sheets of paper and a cover sheet of paper of stronger texture covering one face of said cushion layer, the lateral edges of said cover sheet being folded over and secured to the lateral edges of the top of said liner-sheets, the padding strip provided with a longitudinal medial crease adapted to fold the lateral portions of the strip against each other, whereby the padding strip when opened out on its said crease and placed over an angular surface will tend to be temporarily held in place by the reflex action of its lateral portions. 15

3. A padding strip comprising a cushion layer composed of relatively soft pliable liner-sheets of paper and a cover sheet of paper of stronger texture covering one face of said cushion layer, the lateral edges of said cover sheet being folded over and secured to the lateral edges of the top of said liner-sheets, the padding strip provided with a longitudinal medial crease adapted to fold the lateral portions of the strip against each other, the liner-sheets progressively increasing in width towards the cover sheet so as to tend to maintain said crease. 30

4. A padding strip comprising a cushion layer composed of relatively soft pliable liner-sheets of paper and a cover sheet of paper of stronger texture covering one face of said cushion layer, the lateral edges of said cover sheet being folded over and secured to the lateral edges of the top of said liner-sheets, the padding strip provided with a longitudinal medial crease adapted to fold the lateral portions of the strip against each other, the liner sheets progressively increasing in width towards the cover sheet so as to tend to maintain said crease, and the cover sheet and adjacent liner sheet being fastened together on said crease line. 45

JAMES DUVALL.
